UNITED STATES PATENT OFFICE.

LARRY M. PFLAGER, OF ST. LOUIS, MISSOURI, ASSIGNOR TO DAVIS LOCOMOTIVE WHEEL COMPANY, OF ST. LOUIS, MISSOURI, A CORPORATION OF DELAWARE.

DRAFT-GEAR FOR LOCOMOTIVE ENGINES AND TENDERS.

No. 904,221.

Specification of Letters Patent. Patented Nov. 17, 1908.

Application filed April 25, 1908. Serial No. 429,272.

To all whom it may concern:

Be it known that I, HARRY M. PFLAGER, a citizen of the United States, residing at St. Louis, in the State of Missouri, have invented a new and useful Improvement in Draft-Gear for Locomotive Engines and Tenders, of which the following is a specification.

My invention relates to that class of draft-gear for a locomotive engine or tender in which the coupler is combined with springs and follower-plates having their housing in the pilot-beam or end sill, and has for its object to simplify construction and to enable the coupler-shank or draw-bar to be inserted through the front opening in the pilot-beam parallelly to the longitudinal center of the engine or tender frame, and then moved transversely into service position and attachment to the spring operating member within the said housing, for rendering the draft-gear self-centering within a limited space and reducing the distance between the coupler and the rear side of the pilot-beam to the desired minimum.

The invention consists in features of novelty as hereinafter described and claimed, reference being had to the accompanying drawing forming part of this specification, 30 whereon,

Figure 1, is a top plan view of my improved draft-gear as applied to a locomotive pilot-beam or end sill, broken away at its middle portion to show the interior of the housing thereat for the draft-gear; Fig. 2, a vertical transverse section through the coupler-shank or draw-bar on line 2, 2, in Fig. 1, showing the pilot-beam in front side elevation; Fig. 3, a vertical longitudinal section through the pilot-beam and corresponding section through the draft-gear on line 3, 3, in Fig. 1, and Figs. 4, and 5, vertical transverse sections through the pilot-beam, and corresponding views of the draft-gear 45 on lines 4, 4, and 5, 5, respectively, in Fig. 1.

Like letters and numerals of reference denote like parts in all the figures.

a represents the pilot-beam or end sill of a locomotive engine or tender, which is composed preferably of cast steel integral throughout and in the present case box-shaped in cross section having a forward and downward extension at its middle portion as shown.

55 In the pilot-beam *a* at its middle extended

portion between the respective walls thereof, is formed a receptacle or housing *b* for the springs and adjacent combined parts of the draft-gear, the housing *b* having an opening 1 therefrom through its front wall 2 and front side of the beam *a* thereat, adapted for the free passage therethrough and play of the coupler-shank or draw-bar *c* as hereinafter more particularly referred to.

Through the bottom wall 4 of the housing *b* is formed an opening 5 for the insertion therethrough of a cross-head *d* which is arranged horizontally within the housing *b* at right angles to and in the plane of the draw-bar *c*, the cross-head *d* having in its front side opposite and corresponding to the front opening 1 of the housing *b*, a rectangular-shaped recess 6 of suitable depth, containing a central pocket 7 which is adapted to receive, and having a top depending and bottom upwardly projecting lug 8, and 8', respectively, adapted to hold, the rear end portion 9 of the draw-bar *c*, in the assembled or service position of the parts, one side of the pocket 7 being closed and its other side open and spaced apart from the corresponding end of the recess 6 sufficiently to permit initially of the insertion within that part of the recess 6 of the rear end portion 9, when entered and passed with the draw-bar *c* parallelly to the longitudinal center of the engine frame through the front opening 1, the draw-bar *c* being then moved transversely along the opening 1 and its rear end portion 9 passed laterally into the pocket 7 between the rear wall and the front lugs 8, 8', thereof, in which position it is secured to the cross-head *d* by bolts 10 in the usual manner.

Between and endwise against the cross-head *d* and the front wall 2 of the housing *b*, at each side of the recess 6 and the said center, are arranged the "draft" springs *c* which bear on the bottom wall 4 of the housing *b*, while between and endwise against the cross-head *d* and the rear wall 11 of the housing *b*, in alinement with the "draft" springs *c* are arranged the "buffing" springs *c'*, the springs *c*, and *c'*, being operated by the cross-head *d* on the pulling and buffing movements respectively of the draw-bar *c* without the use of follower-plates, thereby enabling the parts to occupy less space and with less forward projection of the middle portion of the beam *a* and coupler than in the ordinary pilot-beam draft-gear; also by

making the opening 1 in the front wall 2 abnormally wide for permitting the initial passage therethrough of the draw-bar *c* parallelly to the longitudinal center of the 5 engine frame, the adjustment and connection of its rear end portion 9 to the cross-head *d* is readily effected without the necessity of forming clearance-ways therefor in the top or bottom member of the beam which 10 weakens the casting at the part where its maximum strength is required.

For reducing the abnormal width of the opening 1 through the front wall 2 of the housing *b* and limiting the lateral play of 15 the draw-bar *c* therein from its normal central or service position, I interpose between the draw-bar *c* and the bottom of the opening 1, a carrier-plate *f* which extends rearward for a suitable distance within the housing *b*, and on which the draw-bar *c* rides at all 20 times, the plate *f* having two opposite upright lateral flanges 12 which are adapted to reduce the spaces between the draw-bar *c* and the sides of the opening 1 and extend 25 rearward therefrom along the plate *f* parallel and in proximity to the "draft" springs *e* which are thereby held laterally in place.

What I claim as my invention and desire to secure by Letters Patent is:—

30 1. In draft-gear for a locomotive engine or tender, the combination with the end-sill of the frame, of a draw-bar having a suitable head and coupler, a housing formed in and having an opening through the front side of 35 the said sill adapted for the passage therethrough and play of the draw-bar, a "draft" spring and a "buffing" spring alined to each other on each side of the longitudinal center of the said frame within the housing, 40 and adapted to bear at their outer ends respectively, against the front and rear walls thereof, a cross-head intermediate to and adapted to bear against the inner ends of

the said springs, and having a recess in its front side opposite to the said opening for 45 receiving the rear end portion of the draw-bar on its initial passage longitudinally through the said opening, a pocket in the recess adapted to receive and hold the said portion in its ultimate normal central position, means for assembling the springs and cross-head within the housing, and for fixing the draw-bar to the cross-head, substantially as described.

2. In draft-gear for a locomotive engine 55 or tender, the combination with the end sill of the frame, of a draw-bar having a suitable head and coupler, a housing formed in and having an opening through the front side of the said sill adapted for the passage 60 therethrough and play of the draw-bar, a "draft" spring and a "buffing" spring alined to each other on each side of the longitudinal center of the said frame within the housing, and adapted to bear at their outer 65 ends respectively, against the front and rear walls thereof, a cross-head intermediate to and adapted to bear against the inner ends of the said springs, and having a recess in its front side opposite to the said opening for 70 receiving the rear end portion of the draw-bar on its initial passage longitudinally through the said opening, a pocket in the recess adapted to receive and hold the said portion in its ultimate normal central position, 75 means for limiting the play of the draw-bar from its said position toward the sides of the said opening, and for preventing lateral displacement of the "draft" springs within the housing, substantially as de- 80 scribed.

HARRY M. PFLAGER.
